Char. by Candy Atty:

Patented Apr. 7, 1925.

UNITED STATES PATENT OFFICE.

JOHN G. BLESSING, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC CALLING DEVICE.

Application filed January 11, 1921. Serial No. 436,532.

To all whom it may concern:

Be it known that I, JOHN G. BLESSING, a citizen of the United States of America, and a resident of Chicago, Cook County, and State of Illinois, have invented certain new and useful Improvements in Automatic Calling Devices, of which the following is a specification.

My invention relates in general to an automatic calling device and more specifically to an improved type of calling device for use with standard two wire automatic switches or any other type of switches which are operated by opening the line circuit at the telephone.

Among the objects of my invention are to provide, an improved governor for regulating the speed of such a device; a brake of improved character which acts to prevent forcing or speeding the device; an improved means for operating the shunt springs in such a device; improved stop for limiting the movement thereof and to provide other detailed features of improvement which tend to simplify and greatly improve the operation and efficiency thereof and which will be fully described and their operation explained in the following specification.

In Fig. 1 of the drawing I have shown a front view of the calling device of my invention with the cap removed to show the power spring.

Fig. 2 is a rear view showing the operating elements and governor.

Fig. 3 is a view taken from the top of Fig. 1 showing the cam or interrupter with its springs and the shunt springs.

Fig. 4 is another front view of the device with the finger hole dial and number plate removed showing the various gears and other operating parts.

Fig. 5 is a back view of the finger hold dial showing the gear and ratchet devices mounted thereon.

Fig. 6 is a view of the cap which is arranged to snap over the cup spring on the front of the finger hold dial of Fig. 1.

Fig. 7 is a detailed side view of the governor.

Referring now to the drawings I will describe the various parts more in detail and explain the method of operation.

My improved device is composed of a mounting plate 2 upon the front of which

is mounted a finger hole dial 1 by means of a screw 3. This dial has the usual ten finger holes and carries a cup 4 enclosing a clock spring 5, one end of which is fastened in an opening in the side of the cup 4 and the other end of which is slotted to fit over a small lug on one side of the screw 3. As the finger dial is turned it will be understood that tension is stored in the spring 5, the screw 3 being fastened into a threaded opening in the mounting plate 2, and the dial when released will rotate back to normal. A finger stop 6 is mounted on the under side of the cup 2 and projects over the dial 1 to limit its forward movement. A pair of openings 7 are provided in the dial 1 to receive the two prongs 8 of the cap 9 (Fig. 6) which is a thin metal device upon which letters or names are stamped and which snaps into place covering the spring 5. The screw 10 projects through the finger dial and cooperates with a part 11 (Fig. 4) to stop the return movement of the dial.

The mounting plate 2 is cut out of one piece of light metal such as aluminium and has a projecting ring which may be seen in Figure 1 which surrounds the finger dial to protect the same from being bent.

Referring now to Fig. 2 it will be seen that the rear of the plate 2 has a raised shoulder 12 which is circular in form but the outer edge of which is in the form of a circle the center of which is offset from the center of the circle forming the outer edge of the plate 2. The circle forming the inner edge of the shoulder 12 is concentric with the outer edge of the plate 2 so that the shoulder 12 is thicker on one side than on the other and thus also making the distance from the outer edge of the shoulder 12 to the outer edge of the plate 2 greater on one side than on the other. This permits the dial to be mounted in the cup on the telephone base in such a manner as to permit the dial to be nearer horizontal. Just inside the shoulder 12 and lying loosely therein is a circular ring 13 having a base portion and a cylindrical wall. This ring 13 is held in place by a pair of screws 14 which permit it to turn freely. Loosely mounted on a rigid shaft 15 is a governing device 16 which consists of a hub having a gear 17 at its rear end (see Fig. 7) a plate 18, the outer edge of which is grooved and three outwardly extending arms 19 each bent forward at its outer end.

2

and having holes at the outer end of each arm and another hole aligning therewith in the hub. Each arm carries a pin 20 weighted at its outer end and having a leather or other friction surface on the outer ends of the same. It will be seen that as the hub is rotated by means of its gear, the pins 20 are thrown outward by centrifugal force and rub against the inner wall of the ring 13. Firmly attached to one edge of the ring 13 is a wire spring 21 which lies in the groove of plate 18 and at points near its ends is hooked over lugs 22 and 23 on the plate 2. The lug 23 prevents any counter-clockwise movement of ring 13, while the lug 22 is effective to cause any clockwise movement of the ring 13 to be effective to force spring 21 further into the groove of plate 18. Now as the pins 20 rub against ring 13 and tend to turn it clockwise the movement is resisted by the spring 21 and when the friction between pins 20 and ring 13 is above normal this spring 21 presses against the grooved edge of plate 18 thus acting as a brake thereon. A disc cam 24 semi circular in form, of insulating material, is mounted on one end of a shaft which projects through the plate 2 and carries on its other end a gear wheel 25. As this gear 25 is turned it operates the cam 24 to break the contact of the pair of interrupter springs 26 and 27 (Figures 2 and 3) which may be connected in the circuit over which it is desired to transmit impulses. On the other side of the cam 24 are mounted three shunt springs 28, 29 and 30 which may be used to shunt the transmitter and open the circuit of the receiver or may be arranged to shunt both as desired. Under the end of spring 29 is a pin 31 which is inserted in a hole which passes through plate 2. This pin has a shoulder which is pressed against the plate 2 by the tension of spring 29. This pin 31 is at times, when the dial is normal, pressed outward to open the contact of springs 29 and 30 and close springs 28 and 29 in contact as will be explained. Referring to Figure 4 there is shown a view of the front of the calling device with the finger dial 1 removed and the number plate, which fits under the dial and is fastened by screws at 32, removed also. In this figure may be seen a circular spring 33 fastened at one end by screw 34. This spring 33 is tensioned so that it tends to stand away from the plate 2 and carries a raised shoulder 11 which projects toward the finger dial and lies in the path of the screw 10 which projects on the under side of the dial. A pin 35 is firmly secured to the spring 33 and the pin 31 which controls the shunt springs projects through plate 2 and lies under a part of spring 33. The screw 10 in the dial is so positioned that as the dial stands in normal position the screw 10 presses against the shoulder 11 forcing the pin 35 into the path of the gov-

ernor, as shown in Figure 2, and presses the pin 31 in such a manner as to open springs 29 and 30 and close springs 28 and 29 in contact.

On the under side of the finger dial 1 (see Figure 5) is a hub 36, loosely mounted on which is a unit gear and ratchet wheel having ratchet teeth 37 on the side next to the dial and gear teeth 38 underneath. A pawl 40 is secured to the under side of the dial 1 and is held in engagement with the ratchet teeth 37 by a spring 39, so that, as the dial rotates, in one direction the pawl 40 slides over the teeth 37 and the ratchet and gear remain stationary but as the dial returns it carries the ratchet and gear with it.

When the finger dial is mounted in place on the plate 2, the gear teeth 38 mesh with the gear teeth on the pinion 41 which is a unit with the gear 42, which is also loosely mounted on a stud on plate 2 and which lies in a recessed portion of plate 2 which is deep enough to meet the opening in which the governor hub rests, thus permitting the gear 42 to mesh the teeth of the gear 17 (Figures 4 and 7) to turn the governor. The gear 42 also meshes with the teeth of gear 25 to rotate the cam 24.

It is thought that from the above detailed description of the various co-acting parts of my device that it will be clear that, when the subscriber inserts a finger into one of the holes of the dial and draws it forward in a clockwise direction, the screw 10 first leaves the shoulder 11 of spring 33, removing the lock 35 from the path of the governor and permitting springs 28 and 29 to open contact and springs 29 and 30 to close contact, also storing tension in the clock spring 5. When the finger of the operator reaches the stop 6, the dial is released and returns to normal under control of spring 5. The return rotation of the dial is communicated through pawl 40 and teeth 37, through gear wheel 38, to pinion 41 and gear 42. Gear 42 operates the cam 24 through gear 25 and also operates the governor 16 through its gear 17. The governor 16 governs the speed of the return movement as described and as the dial returns to normal spring 10 again meets the shoulder 11 to project the stop 35 into the path of the governor to stop further rotation and also operates the shunt springs to close springs 28 and 29 and open springs 29 and 30.

It will be seen therefore that I have provided a very efficient type of automatic calling device which has a number of new and novel features of improvement and having fully described the said details of improvement and the method of operation, what I consider to be new and desire to have protected by Letters Patent will be pointed out in the appended claims.

What I claim as my invention is:

1. In a calling device, a governor for regulating the speed of the impulse mechanism, said governor comprising a gear driven hub having radially projecting arms, a weighted pin loosely inserted in each arm and having an unrestrained endwise movement therein, and a circular surface surrounding said governor and frictionally engaged by said pins as the mechanism operates to retard the same. 5
2. In a calling device, a governor for regulating the speed of the impulse mechanism, said governor comprising a gear driven hub having radially projecting arms, a weighted pin loosely inserted in each arm and movable endwise therein, a movable circular surface surrounding said governor and frictionally engaged by said pins as the mechanism operates to retard the same, and a brake for also retarding said mechanism when said surface is moved. 10
3. In a calling device, a governor having a frictional surface and a plurality of frictional surfaces riding thereon, said governor nor having additional frictional surfaces engaging only when the friction produced by said first surfaces exceeds that which is normally produced, one of said last frictional surfaces being in the form of a spring which constitutes the means by which said last frictional surfaces are normally prevented from engaging. 15
4. In a calling device, a governor having a frictional surface and a plurality of members engaging therewith, additional frictional surfaces, said first surface comprising a normally stationary ring surrounding said additional surfaces and movable when the friction produced by said members exceeds a given amount to bring said additional surfaces into engagement. 20
5. In a calling device, a centrifugal governor for regulating the speed of the impulse mechanism, said governor comprising a series of radially extending arms carrying loosely mounted pistons, and a ring surrounding said pistons and engaged thereby when the mechanism is operating, said ring stationary in the normal operation of the device, but movable with an increase of speed to apply a brake to said governor. 25
6. In a governor, a rotatable shaft, a floating ring concentric with said shaft, friction devices attached to said shaft and adapted to engage the inside surface of said ring under the action of centrifugal force, and braking means controlled by said ring for limiting the speed of said shaft. 30
7. In a governor, a rotatable shaft, a floating ring concentric with said shaft, friction devices attached to said shaft and adapted to engage the inside surface of said ring under the action of centrifugal force, when the same is moved by the engagement therewith of said friction devices, and a brake surface secured to the shaft and engaged by said braking member when the same is operated. 35
8. In a governor, a rotatable shaft, a floating ring concentric with said shaft, friction devices attached to said shaft and adapted to engage the inside surface of said ring under the action of centrifugal force, a grooved pulley mounted on said shaft, and a steel wire arranged to engage the surface of the groove when the said ring moves responsive to the engagement of said friction devices. 40
9. In a speed governor, a normally stationary ring, means inside said ring for engaging the same due to centrifugal force when the governor is in operation, supporting means for said ring permitting the same to move responsive to the resulting friction, and a friction retarding device brought into operation by movement of said ring. 45
10. In a speed governor, a normally stationary ring, a rotatable member inside said ring and having means operated by centrifugal force for engaging the ring when the said member is rotated, supporting means permitting said member to move responsive to the resulting friction, and a retarding device brought into frictional engagement with said member by movement of said ring. 50
11. In a speed governor, a normally stationary ring, a spoked wheel having a grooved hub inside said ring, weights on the ends of said spokes adapted to engage the inside surface of said ring when the wheel is rotated, supporting means for said ring permitting the same to move when so engaged, a wire lying in the groove in said wheel, and a connection between the ring and wire whereby the latter is forced into frictional engagement with the sides of the groove when the ring is moved. 55
12. A speed regulating governor comprising a gear driven member carrying a plurality of frictional members, each frictional member having sufficient space in said gear driven member to allow an unrestrained movement therein, and a circular surface surrounding said frictional members engaged by them as the mechanism rotates to maintain the speed constant. 60

Signed by me at Chicago, Illinois, this 7th day of January, 1921. 120

JOHN G. BLESSING.
